(57) CLAIM

The ornamental design for a toaster pick, as shown and described.

DESCRIPTION

FIG. 1 is a front perspective view of a toaster pick, showing my new design;

FIG. 2 is a front elevational view of FIG. 1;

FIG. 3 is a rear elevational view of FIG. 1;

FIG. 4 is a left-side elevational view of FIG. 1;

FIG. 5 is a right-side elevational view of FIG. 1;

FIG. 6 is a top plan view of FIG. 1; and,

FIG. 7 is a bottom plan view of FIG. 1.

The regular broken lines in the figures depict portions of the toaster pick that form no part of the claimed design.

1 Claim, 3 Drawing Sheets
